UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,070,285.

Specification of Letters Patent. Patented Aug. 12, 1913.

Application filed September 10, 1907. Serial No. 392,813.

To all whom it may concern:

Be it known that I, LANSING ONDERDONK, a citizen of the United States, residing at New York, in the county of New York, State 5 of New York, have invented certain new and useful Improvements in Looper-Operating Mechanisms for Sewing-Machines, of which the following is a description, reference being had to the accompanying drawing and to the letters and figures of reference marked thereon.

My invention relates to looper-operating mechanisms for sewing-machines, and has for its object to provide a machine having a 15 lower continuously rotating shaft with a looper, and means for positively operating said looper from said rotary shaft.

A further object of my invention is to provide a looper support, which shall be 20 self-lubricating.

Still further objects of my invention will in part be obvious, and will in part be more fully hereinafter set forth.

In the drawings which show by way of 25 illustration one embodiment of my invention,—Figure 1 is a sectional view of a portion of a sewing machine embodying my looper mechanism, said section being taken on a line parallel with the line of feed; 30 Fig. 2 is a bottom plan view of a sewing machine embodying my invention; Fig. 3 is a detail sectional view, showing the looper in side elevation; Fig. 4 is a sectional view of the looper-supporting shaft; and Fig. 5 35 is a plan view of the looper-supporting shaft, with the supporting collar for the looper removed.

The bed plate 1 has rising therefrom an overhanging arm 2, in which reciprocates a 40 needle bar 3, carrying a needle 4 at its lower end.

The feed bar 5 is pivoted to a feed rocker 6, mounted on a shaft 7, which receives a rocking movement through the arm 8 from 45 an eccentric on the main shaft, which is mounted in the overhanging arm. The feed bar 5 receives its up and down movement from a crank arm 9, mounted on a shaft 10, which is oscillated by a yoke 11, which engages an eccentric on the shaft 12. Said 50 shaft 12 is continuously rotated, by means of a belt 13, from the main shaft in the overhanging arm. The crank arm 9 carries a block 14, on its forward end, which is located

in the fork of the feed bar 5. The feed bar 55 carries the usual feed dog, which is omitted from the drawing for the sake of clearness.

The looper 15, as shown in the drawings, is of the thread-carrying type, and is mounted in a carrier 16, which is clamped to the 60 forward end of a sleeve 17, shown in detail in Fig. 4. The sleeve 17 is mounted upon the looper-supporting shaft 18. The looper-supporting shaft 18, as shown in Figs. 4 and 5, is reduced at its forward end, so that the 65 sleeve 17 is of the same diameter as the outer end of the shaft 18. A wear washer 19 is placed on the reduced portion of the shaft 18, between the end of the sleeve 17, and the body portion of the shaft 18. The 70 washer 20 is also placed on the reduced end of the shaft 18, and secured thereto by a nut 21.

The shaft 18 is bored centrally as at 22 (see Fig. 4). The bore 22 in the enlarged 75 portion of the shaft 18 is filled with a suitable oil-receiving packing. A screw 23 is threaded into the smaller end of the bore in the shaft 18, and a screw 24 closes the other end. The shaft 18 is provided in its outer 80 surface with a spiral groove 25, which extends throughout the length of said shaft. The shaft 18 is also provided with openings 26 which lead at intervals from the inner part or bore 22 to the spiral groove 25. By 85 this form of construction, the oil which is contained in the central part of the shaft 18 is gradually fed through the openings 26 into the spiral groove in the outer surface of the shaft 18. Suitable openings 27, 27, are 90 also provided at intervals through the sleeve 17, so that the oil may pass to the outer surface of said sleeve.

The looper-supporting shaft 18 is mounted in suitable bearings 28, 29, and said shaft 95 is free not only to oscillate in said bearings, but to be moved longitudinally therein. The looper carrier 16 is clamped on the outer end of the sleeve 17, by means of a clamping screw 30. A collar 31 is secured at the other 100 end of the sleeve 17, at a point intermediate the bearings 28 and 29. Said sleeve 31 carries an outwardly extending arm 32. The main shaft 12 extends through the bearing 33, secured to the under side of the bed plate, and has mounted on its forward end a crank disk 34, carrying a ball socket bracket 35. The link 36 is provided with a

ball at one end which fits into the socket in the bracket 35, and at the other end said link is pivoted by a universal joint 37 to the arm 32.

- 5 It will appear from the above description that the connection between the link 36 and the crank disk 34 is located at one side of the axis of the rotating shaft, while the other end of the link, which is connected to the looper support is also at one side the axis of said rotating shaft. The link is therefore inclined, or set by an acute angle to the axis of the shaft in all of its positions during the rotation of the shaft. This arrangement of the link relative to the shaft causes the shaft to impart not only a gyroscopic, but also an endwise movement to the link, and this endwise movement of the link oscillates the looper.
- 10 The looper support 18 has a collar 38 secured thereto. A lever 39 pivoted to a stud 40, carried by the under side of the bed plate is vibrated by means of a link 41, which engages an eccentric 42 on the forward end of the shaft 12 at one end, and which is pivoted as at 43 to the lever 39 at the other end. A link 44 connects the opposite end of the lever 39 to the collar 38. As the shaft 12 is rotated the eccentric 42 will vibrate the lever 39 and said lever will in turn reciprocate the looper support 18 longitudinally in its bearing, and thus give to the looper a lateral movement. The timing of the parts is such that as the main shaft 12 rotates, the looper is oscillated through the link 36 and moves forward from the position shown in Fig. 2, into the needle loop. As the looper approaches the forward end of its stroke, the eccentric 42 through the lever 39 moves said looper laterally to give thereto the needle-avoiding movement. The looper is next retracted by the link 36, and again through the lever 39 moves laterally back to the first position.
- 15 As noted in Fig. 2 of the drawing, the ball socket bracket 35 is shown adjustably connected to the crank disk 34. The crank disk 34 is preferably provided with a T-slot and the bracket 35 is provided with a rib extending into the T-slot and a T-bolt 35² having its head located in the T-slot, extends through a lug on the bracket 35 and a suitable nut carried by said bolt serves to clamp the bracket in its adjusted position. By loosening the nut on the bolt 35², the bracket 35 may be adjusted across the face of the disk 34 and the stroke of the looper thus varied.
- 20 It will thus be seen that I have provided a looper mechanism, wherein the looper is operated from a continuously rotated shaft through positive means, and by said mechanism, I am enabled to drive my looper at a very high speed.
- 25 While I have described the shaft 12 as a continuously rotated shaft, it is obvious

that from certain aspects of my invention said shaft may be oscillated.

Having thus described my invention, what I claim as new and desire to secure by Letters Patent, is:

- 70 1. A looper-operating mechanism, including in combination, a rotating shaft, a looper support arranged at right angles thereto, the axis of the looper support, and the axis of said shaft, lying substantially in the same plane, a looper carried thereby, a crank disk mounted on the forward end of said shaft, a link connected to said crank disk and to said looper support for oscillating said looper support, and means having an independent connection with the rotating shaft for moving said looper support longitudinally.
- 75 2. A looper-operating mechanism, including in combination, a rotating shaft, a looper support arranged at right angles thereto, a looper carried thereby, a crank disk mounted on the forward end of said shaft, a link connected to said crank disk and to said looper support for oscillating said looper support, a lever connected to said looper support, and means for vibrating said lever, whereby the said looper support is moved longitudinally.
- 80 3. A looper mechanism, including in combination, a rotary shaft, a looper-support arranged at right angles thereto, a looper mounted on the ends of said looper support, a crank disk mounted on the forward end of said shaft, a link having a ball stud secured to said crank disk, means for securing the opposite end of said link to said looper support, and means for moving said looper support longitudinally.
- 85 4. A looper mechanism, including in combination, a rotary shaft, a looper support arranged at right angles thereto, a looper mounted on the end of said looper support, a crank disk mounted on the forward end of said shaft, a link having a ball stud secured to said crank disk, means for securing the opposite end of said link to said looper support, a lever, an eccentric mounted on said shaft and connected to said lever, and means for connecting said lever to said looper support, whereby the same is moved longitudinally.
- 90 5. A looper mechanism, including in combination, a looper support having a reduced portion, a sleeve mounted on said reduced portion and of the same diameter as said looper support, a looper mounted on one of said parts, means for oscillating said part supporting said looper, and means for moving said support and sleeve longitudinally.
- 95 6. The combination of a looper support, having an oil-receiving recess formed centrally thereof, and openings leading from said oil-receiving recess to the exterior of said looper support, and a looper carried by said looper support.
- 100 105 110 115 120 125 130

5. In combination with a looper support, having an oil-receiving recess located centrally thereof, openings leading to the exterior of said support, a spiral groove formed on the outer surface of said support, and connecting said openings, a sleeve mounted on said support, and a looper secured to said sleeve.

10. In combination with a looper support, having an oil-receiving recess centrally thereof, a screw cap for closing said recess, openings leading from said recess to the outer surface of said support, a sleeve mounted on said support, openings leading through said sleeve, bearings in which said looper support is mounted, and a looper carried by said looper support.

15. In combination with a looper support, having an oil-receiving recess centrally thereof, a screw cap for closing said recess, openings leading from said recess to the outer surface of said support, a sleeve mounted on said support, openings leading through said sleeve, bearings in which said looper support is mounted, a looper carried by said looper support, and means for oscillating said sleeve on said looper support.

20. In combination with a looper support, having an oil-receiving recess centrally thereof, a screw cap for closing said recess, openings leading from said recess to the outer surface of said support, a sleeve mounted on said support, openings leading through said sleeve, bearings in which said looper support is mounted, a looper carried by said looper support, and means for oscillating said sleeve on said looper support.

25. In combination with a looper support, having an oil-receiving recess centrally thereof, a screw cap for closing said recess, openings leading from said recess to the outer surface of said support, a sleeve mounted on said support, openings leading through said sleeve, bearings in which said looper support is mounted, a looper carried by said looper support, and means for oscillating said sleeve on said looper support.

30. 11. A looper mechanism including in combination a rotating shaft, a looper support, a looper carried thereby, means for moving said looper in a direction substantially at right angles to the axis of said shaft, and means for moving said looper in a direction parallel with a plane embracing the axis of said shaft, said last named means including a member carried at the outer end of said shaft, a link inclined to the axis of said shaft, and having a universal joint connection with said member at a point at one side of the axis of said shaft, and means for connecting the outer end of said link to said looper support at a point at one side of the axis of said shaft, whereby said link will be given a gyratory and endwise movement, and thereby impart an oscillating movement to said looper.

35. 12. A sewing machine, including in combination a work support, a rotating shaft, extending longitudinally of said work support, a looper, a looper support located between the end of said shaft and the end of the work support, means for moving said looper transversely of said work support, and

means for moving said looper longitudinally of said work support, said last named means including a member carried at the end of said shaft, a link inclined to the axis of said shaft and having a universal joint connection with said member at a point at one side the axis of said shaft, and means for connecting the outer end of said link to the said looper support, the outer end of said link being disposed at one side of the axis of said looper shaft, whereby said link will be given a gyratory and endwise movement, and thereby impart an oscillating movement to said looper.

40. 13. A sewing machine, including in combination a work support, a rotating shaft, extending longitudinally of said work support, a looper, a looper support located between the end of said shaft and the end of the work support, means for moving said looper longitudinally of the work support, including a member carried at the outer end of said shaft, a link having a ball and socket connection with said member at a point at one side of the axis of said shaft, said link being inclined to the axis of said shaft, means for connecting the outer end of said link to the looper support, the outer end of said link being disposed at one side of the axis of said rotating shaft, whereby said rotating shaft will impart a gyratory and endwise movement to said link and thereby move the looper longitudinally of the work support.

45. 14. A sewing machine, including in combination a work support, a rotating shaft, extending longitudinally of said work support, a looper, a looper support located between the end of said shaft and the end of the work support, means for moving said looper longitudinally of the work support, including a member carried at the outer end of said shaft, a link having a ball and socket connection with said member at a point at one side of the axis of said shaft, said link being inclined to the axis of said shaft, means for connecting the outer end of said link to the looper support, the outer end of said link being disposed at one side of the axis of said rotating shaft, whereby said rotating shaft will impart a gyratory and endwise movement to said link and thereby move the looper longitudinally of the work support, and means independent of said link for moving said looper transversely of said work support.

50. 15. A sewing machine including in combination, a rotating shaft, a looper support arranged in front of one end of said shaft and at substantially right angles thereto, a looper mounted on said support, a crank disk carried on the end of said shaft and having a ball socket formed therein, a member connected to the looper carrier for moving the looper in one direction; a link hav-

- ing a ball on one end engaging said ball socket in the crank disk and having a universal connection with the member connected with the looper carrier, and means having an independent connection to the rotating shaft for moving the looper in a direction substantially at right angles to the first named direction.
16. A sewing machine including in combination, a rotating shaft, a looper support arranged in front of one end of said shaft and at substantially right angles thereto, a looper mounted on said support, a crank disk carried on the end of said shaft and having a ball socket formed therein, a member connected to the looper carrier for moving the looper in one direction, a link having a ball on one end engaging said ball socket in the crank disk and having a universal connection with the member connected with the looper carrier, said shaft having an eccentrically disposed member, and means operated by said eccentrically disposed member for moving the looper in a di-

rection substantially at right angles to the first named direction.

17. A sewing machine including in combination, a shaft, a looper support arranged in front of one end of said shaft, and substantially at right angles thereto fixed bearings therefor, a looper mounted on said support, a member carried by the forward end of the shaft, a member connected to the looper support for moving the looper in one direction, a link having an eccentric universal connection with the member on said shaft, and a universal connection with the member connected to the looper support, and means having an independent connection with the operating shaft for moving the looper in a direction substantially at right angles to the first named direction.

In testimony whereof I affix my signature, in presence of two witnesses.

LANSING ONDERDONK.
